Des. 213,165
Patented Jan. 7, 1969

213,165

ELECTRIC SHAVER

Melvin H. Boldt, Glenview, Ill., assignor to Schick Electric
Inc., Lancaster, Pa., a corporation of Delaware

Filed Jan. 16, 1968, Ser. No. 10,180

Term of patent 14 years

U.S. Cl. D95—3
Int. Cl. D28—03

FIG. 1

FIG. 3

FIG. 2

FIG. 4

FIG. 5

FIG. 6

FIG. 1 is a perspective view from one side and top of an electric shaver showing my new design;

FIG. 2 is a top view thereof;

FIG. 3 is a view of the side thereof not seen in FIG. 1;

FIG. 4 is a bottom view thereof;

FIG. 5 is a rear view thereof; and

FIG. 6 is a front view thereof.

The dominant features of my design reside in the portions shown in full lines on the drawing.

I claim:

The ornamental design for an electric shaver, substantially as shown and described.
